EASEL FOR A CIRCUIT BOARD OR THE LIKE

Dallas R. Lynch, Little Rock, Ark., assignor to the United States of America as represented by the Secretary of the Army

Filed Mar. 30, 1965, Ser. No. 84,538

Term of patent 14 years

(Cl. D80—9)

FIG. 3

FIG. 2

FIG. 1 is a front perspective view of an easel for a circuit board or the like showing my new design, the broken line fragmentary showing of a desk (or table) with the drawer extended is merely for illustrative purposes only.

FIG. 2 is a front view of the circuit board or the like shown in FIG. 1; and

FIG. 3 is a sectional view taken on the line 3—3 of FIG. 1.

The design described herein may be reproduced and used by or for the Government for governmental purposes without the payment to me of any royalty thereon.

I claim:

The ornamental design for an easel for a circuit board or the like as shown and described.
